ARTIFICIAL LEG

Terry O. Carroll, Lakeland, Fla., assignor of one-fourth to D. E. Dunbar, Lakeland, Fla.

Application March 31, 1933, Serial No. 663,812

3 Claims.

(Cl. 3—2)

This invention relates to artificial legs and particularly to that type of leg for use in connection with an amputation above the knee.

One of the objects of the invention is to provide a leg in which the center of gravity of the lower or shin portion is adjustably shiftable laterally with respect to a plumb line passing through the axis of the knee bolt whereby the character of the stride may be improved and 10 made to correspond with that of the sound leg.

Another object of the invention is to provide an eccentric bearing for the knee joint adjustable as to throw so that the axis of oscillation can be shifted laterally or up and down, for the above 15 stated and other purposes.

Other objects of the invention will appear as the following description of a preferred and practical embodiment thereof proceeds.

In the accompanying drawing which forms a 20 part of the following specification, and throughout the several figures of which the same characters of reference have been employed to denote identical parts:

Figure 1 is a view in elevation of the knee joint 25 of a leg embodying the principles of my invention;

Figure 2 is a section taken along the line 2—2 of Figure 1;

Figure 3 is a section taken along the line 3—3 30 of Figure 2;

Figure 4 is a section taken along the line 4—4 of Figure 2;

Figure 5 is a view in perspective of the roller.

Referring now in detail to the several figures, 35 the numeral 1 represents the thigh portion of the artificial leg connected to the shin portion 2 by a knee bolt 3. The knee bolt may be of conventional construction and is non-rotatably fixed by means of threads 4 into eyes 5 at the top of the 40 eye plates 6, the latter being secured in any suitable manner as by the rivets 7 to the thigh portion. A lever 8 is fixed to the knee bolt 3 in known manner and the suspender or shoulder strap 9 passes around a roller 10 mounted in a 45 bifurcation at the front of the lever 8. The function of the shoulder strap is to hold the thigh portion upon the stump as well as to give the shin portion 2 an initial forward impulse when the thigh is lifted.

50 It is customary to mount the thigh portion 1 directly upon the knee bolt 3, but such construction allows of no adjustment and the stride which such an articulation permits is subject to some defects. In the first place, the nature of the 55 stride cannot be modified and therefore, it can-

not be made to correspond to little peculiarities in the natural stride of the sound leg. Furthermore, when the thigh portion is raised in the act of stepping, the shin portion gravitates slowly to its forward repose position producing a drag of 5 the foot upon the ground to avoid which the wearer accustoms himself to a swaying stride in order that the artificial leg shall clear the ground.

Another defect of the conventional articulation 10 is that when the wearer of the leg starts to place his weight upon it, there is some chance of it buckling and causing him to fall.

The present invention provides an improvement over the conventional joint, by mounting a 15 pair of bearing discs 10 and 11 eccentrically upon the knee bolt near the opposite ends thereof, and journaling the thigh portion upon these discs. The eccentric discs 10 and 11 are displaceable about the axis of the knee bolt and securable in 20 any desired position of adjustment by means such as a series of holes 12 formed in the eccentric and a set screw 13 passing through a threaded aperture in the plate 6 and into one of the holes 12. Through the adjustment thus provided, the knee 25 bolt is shifted forward or backward. The thigh portion 1 is provided with suitable bearing apertures encompassing the discs 10 and 11 and suitably lined as with leather as indicated at 14.

It is assumed that in the leg as normally articulated, the center of gravity of the thigh portion lies in a plumb line passing through the axis of the knee bolt. By means of the present invention, the throw of the eccentric may be adjustable forwardly as indicated in Fig. 1 so that the 35 center of gravity of the thigh portion, which passes through the center of the eccentric is shifted forwardly of the plumb line through the knee bolt, as indicated at 15 in Figure 1. When the weight of the wearer is upon the leg, it is 40 obvious that the center of gravity of the thigh portion being forward of the center of gravity of the shin portion which is in the said plumb line, will prevent the leg from buckling into a flexed 45 position.

Furthermore, the relative forward and backward adjustment of the knee bolt also moves the lever 8 and roller 10' which is engaged by the shoulder strap forward or backward, permitting the shoulder strap to pick up the shin portion 2 50 a trifle sooner or later with respect to the lifting of the thigh so that an adjustment can be effected that will prevent the toe dragging, and permit the artificial member to move through an arc directly beneath the body, and eliminating the 55

side swing so common in walking when an artificial leg is employed.

One of the principal features of the invention is that the eccentric discs can be adjusted so as 5 to cause the locomotion of the artificial limb to simulate very closely the natural motion of the sound limb.

It will be observed that with the construction 10 of the present invention, all the parts are substantially flush with the leg portions with which 15 they engage and there are no projecting parts to catch and tear the clothing of the person wearing the artificial leg.

It is also obvious that the eccentric discs may 15 be adjusted at will without the necessity of dis- 20 assembling the leg or of removing the clothing.

While I have in the above description disclosed 25 what I believe to be a preferred and practical form of the invention, it is to be understood that the details of construction as herein shown and described are merely by way of limitation and not to be construed as restricting the scope of the invention as claimed.

What I claim is:

25 1. Artificial leg comprising thigh and shin por-

tions, a knee bolt pivotally connecting said por- 5 tions, said knee bolt being provided with eccentric portions, said thigh portion being journalled upon said eccentric portions, the latter being ad- justably displaceable for shifting the knee bolt laterally, a lever fixed to said knee bolt extending radially forwardly thereof, and a shoulder strap roller at the end of said lever.

2. Artificial leg comprising thigh and shin por- 10 tions, a knee bolt pivotally connecting said por- 15 tions, and non-rotatably mounted in said shin portion, a lever fixed to said knee bolt and ex- 20 tends forwardly, a suspender associated with the forward end of said lever, bearing disks ec- 25 ccentrally mounted on said knee bolt, a thigh portion journalled on said eccentrically mounted disks, and means for adjustably displacing said disks for shifting the knee bolt and lever laterally.

3. Artificial leg as claimed in claim 2, the ad- 20 justing means comprising a series of holes in said 25 discs, an aperture in said thigh portion with which said series of holes are selectively regis- trable and a set screw passing through said aper- ture and a selected one of said holes.
